UNITED STATES PATENT OFFICE.

JOHN D. LUTTRELL, OF BENTON HARBOR, MICHIGAN, ASSIGNOR TO ELMER M. BARNES, OF ST. JOSEPH, MICHIGAN.

CONCRETE-MIXER.

No. 882,830.

Specification of Letters Patent. Patented March 24, 1908.

Application filed January 25, 1907. Serial No. 354,055.

To all whom it may concern:

Be it known that I, JOHN D. LUTTRELL, a subject of the King of Great Britain, and a resident of Benton Harbor, Michigan, have 5 invented a certain new and useful Improvement in Concrete-Mixers, of which the following is a specification.

My invention relates to mixers, and more especially to that class of mixers for mixing 10 the ingredients of concrete, and consists of means whereby the heavier particles of the mixture are so combined with the lighter portions that the two cannot become unequally distributed and separated, as fully set forth 15 hereinafter and as illustrated in the accompanying drawing, in which

Figure 1 is a sectional elevation of a mixer specially adapted for concrete and embodying my invention. Fig. 2 is a sectional plan 20 on the line 2—2, Fig. 1. Figs. 3 and 4 are perspective views of different elements of the stirrers.

The frame of the apparatus is of any suitable construction but has a trough or pan B 25 suitably mounted, and above this pan is a cross-head C rotatable about a central vertical axis. As shown there is a stationary post 1, about which turns a sleeve 2 to which the cross head C is fixed, the sleeve being closed 30 at its upper end and resting upon a ball bearing at the top of the post 1, and being provided with a gear 3 engaging a gear 4 on a driving shaft 5 suitably supported by the frame.

35 To one arm 6 of the cross head C is suspended a rake D having vertical teeth 8, curved and touching the bottom of the pan at their lower ends, and to the other arm 9 of the cross-head is pivoted a stirrer E in the 40 form of a curved grid having horizontal bars 10, the lower edge also resting on the bottom of the pan.

The sleeve 2 is provided with a bracket 12 on which is supported a water tank F having a port at the bottom communicating with a spray device G and with a valve 13, and means for opening and closing it, and to the sleeve 2 is pivoted at x a box H, having a perforated bottom and sliding valve 19. An 50 arm 14, pendent from box H, carries a roller 15 that bears on the serrated edge 16 of the pan B.

The above described apparatus is intended

principally for mixing cement and sand. Such mixers as ordinarily constructed have, 55 in many cases, proved to be defective because of the neglect to recognize the fact that cement is much heavier than sand and that when cement and sand are deposited simultaneously in a receptacle and agitated, the 60 cement will quickly find its way to the bottom and remain there, the sand rolling over without mixing with the cement, so that but a very imperfect mixture is secured with a detrimental want of uniformity in the result. 65 By the above described apparatus I avoid this result, inasmuch as the sand is in the first instance placed in the pan B in the desired quantity and the proper proportion of cement is placed in the box H, and the apparatus is then put in operation, the valves 70 13 and 19 being open.

As the sleeve 2 revolves, the box H is agitated from the traveling of the roller 15 over the serrated edge 16 and the cement is gradually deposited upon the body of the sand. The latter is agitated in one direction by the curved teeth 8 of the rake D and broken up in the opposite direction by the horizontal bars of the grid F so that the particles are 80 thoroughly distributed and agitated in their relative positions during the time that the cement is being gradually spread over the top and thus intimately mixed with the particles of sand, while at the same time the water is sprayed upon the matter in the pan, and as this spraying occurs before the cement has time to find its way to the bottom, it tends to cause the particles of cement to 85 adhere to the particles of sand, with the result that by the time the box H is emptied, the particles of cement and sand have become uniformly distributed among each other and there is a regular and uniform mixture in the pan. It will be seen that the teeth of 90 the rake D serve to divide the mass of the mixture on vertical lines, while at the same time, as they are curved, they tend to carry the bottom portions up towards the top, while the bars of the grid F tend to separate 100 the mass horizontally and also to carry the bottom portion upward and bring it over the top portion, thereby greatly facilitating the intimate admixture of the particles.

It will of course be evident that various 105 kinds of stirring and mixing blades may be

employed in connection with the means for feeding the cement gradually to the mass of sand, and that other means may be employed for spraying the water and for agitating the cement box or receptacle.

The contents of the pan may be removed in any suitable manner, but preferably a portion 21 of the bottom is hinged so that it can be swung down, and is held in a horizontal position by a vertical catch 22.

Without limiting myself therefore to the precise construction and arrangement of parts shown I claim as my invention:

1. In a mixing apparatus the combination of a pan, a shaft arranged centrally in respect to the pan, mixers carried by the shaft, a receptacle having a perforated bottom for pulverized material, means for agitating the receptacle, means for spraying water upon the material in the pan as gradually depos-

ited therein, and means for rotating the shaft together with the receptacle. 25

2. The combination of the pan, a rotatable cross-head, a curved rake and a curved grid connected with said cross-head, a water tank, and a receptacle having a perforated bottom supported to rotate with the cross head, and means for agitating the receptacle. 30

3. The combination with the pan having a serrated edge, its spraying device and receptacle having a perforated bottom, of a bracket extending over the receptacle and provided with a roller resting upon the edge of the pan. 35

In testimony whereof I affix my signature in presence of two witnesses.

JOHN D. LUTTRELL.
